United States Patent Office.

PETER PARADIS AND ROBERT REILLY, OF ROCHESTER, NEW YORK.

Letters Patent No. 65,421, dated June 4, 1867.

CENTRE PLATE FOR STOVE TOPS.

The Schedule referred to in these Letters Patent and making part of the same.

TO ALL WHOM IT MAY CONCERN:

Be it known that we, PETER PARADIS and ROBERT REILLY, of Rochester, in the county of Monroe, and State of New York, have invented certain new and useful improvements in the construction of the "Centre Plates of Cooking Stoves;" and we do hereby declare that the following is a full, clear, and exact description thereof, reference being had to the accompanying drawings making part of this specification, in which—

Figure 1 is a top view or plan of our invention.

Figure 2 is an inverted view of the same, with a portion of the lining, *g*, of the long centre broken away.

Figure 3 is a transverse section of the short centre plate *B*, with its lining *g*, through the plane of the red line *n* in figs. 1 and 2.

Like letters indicate corresponding parts in the several figures.

This invention consists in dividing the centre plates of stove tops, and so connecting the parts that any desired amount of expansion and contraction is permitted without producing any strain upon the said top plates.

To enable others to make and use our invention, we will describe its construction.

We make the centre plates *B* and *D* about in the usual manner, and provide them with a lining, *g*, if desired. We divide the plates *B* and *D* at *a*, as shown in fig. 1, and provide one half of each with a projecting lug, fitted to slide in a recess in the opposite half, as indicated by the dotted lines *b* in figs. 1 and 2. The two parts may be connected together by inserting a rivet through a short slot formed in the shank or lug *f*, and attached together by the rivets *r*, the lining plate also being slotted to receive the rivets. It will be seen that by either of these arrangements the half plates may readily be extended or contracted, and yet the parts retain their relative position otherwise. The long and short plates *B* and *D* are cast with suitable studs or pins *i*, fig. 2, and the stove top cast with corresponding holes to receive them. There are similar holes, *e*, in the long centre plate to receive the pins of the inner end of the short plates, and when the stove is made in the long centre plate to receive the pins of the inner end of the short plates, and when the stove is mounted the centre plates are extended, leaving the joints open, as shown in fig. 1. Then, when the metal is expanded by the heat, the joint gradually becomes closed, and without producing any strain upon any portion of the castings. The ordinary supporting stud may be cast upon the lining of the long centre plate.

It is believed that this change in the construction of this portion of stove plates will wholly avoid the great liability of breakage of the top plate, and of the warping of the centre plates, one or the other of which is almost sure to occur with the ordinary construction.

What we claim as our invention, and desire to secure by Letters Patent, is—

Dividing the centre plates of cooking-stove tops transversely through the narrow portion, and connecting them by loose or sliding joints, substantially in the manner and for the purposes herein shown and described.

PETER PARADIS,
ROBERT REILLY.
